UNITED STATES PATENT OFFICE.

JOSEPH E. BURGESS, OF ST. LOUIS, MISSOURI, ASSIGNOR TO MORE-JONES BRASS & METAL COMPANY, OF ST. LOUIS, MISSOURI, A CORPORATION OF MISSOURI.

COMBINATION STRAIN-PLATE AND REMOVABLE TROLLEY-FROG.

1,272,208.

Specification of Letters Patent.

Patented July 9, 1918.

Application filed August 1, 1914. Serial No. 854,453.

To all whom it may concern:

Be it known that I, JOSEPH E. BURGESS, a citizen of the United States of America, and a resident of the city of St. Louis and State 5 of Missouri, have invented certain new and useful Improvements in Combination Strain-Plates and Removable Trolley-Frogs, of which the following is a specification.

The primary object of this invention is to 10 provide an improved trolley switch construction whereby the trolley frog can be removed and a new frog placed without disturbing the guy wires and trolley wires.

Another object of this invention is to provide 15 an improved strain plate in combination with a removable trolley frog.

A further object of this invention is to provide 20 a strain or supporting plate that is adapted to hold the trolley wires independently of the frog.

Other and further objects will appear in the specification and be specifically pointed out in the appended claims, reference being had to the accompanying drawings exemplifying the invention, and in which,

Figure 1 is a plan view of the strain plate used in combination with a removable trolley frog.

Fig. 2 is an inverted view of Fig. 1.

Fig. 3 is a plan view of a removable trolley frog which is adapted to be used in combination with a strain plate.

Fig. 4 is an inverted view of Fig. 3.

Fig. 5 is a plan view of a strain plate, similar to Fig. 2, but showing the parts relating thereto assembled therewith.

Fig. 6 is a side elevation of Fig. 5.

Fig. 7 is a longitudinal section taken on the line VII—VII, Fig. 5.

Fig. 8 is a longitudinal section taken on the line VIII—VIII, Fig. 5.

Fig. 9 is an enlarged cross section taken on the line IX—IX, Fig. 5.

Fig. 10 is an enlarged cross section taken 45 on the line X—X, Fig. 5.

Fig. 11 is an enlarged cross section taken on the line XI—XI, Fig. 5.

Fig. 12 is an enlarged end view of one of the approaches.

Fig. 13 is a view showing the opposite end of the approach shown in Fig. 12.

In the present construction of trolley switches, the trolley frog in reality is the switch itself, the trolley wires and guy wires

being connected to the frog. When the frog has become worn and it is required to remove it and replace it by a new frog, the guy wires and trolley wires have to be disconnected. This necessitates block and tackle to prevent the trolley wires from falling until a new frog has been secured to the guy wires so that the trolley wires can be in turn secured to the new frog. This task is quite laborious and takes considerable time.

In this improved construction, the strain plate, or supporting plate, 1 is adapted to be permanently held in position by the guy wires, the connecting wires, in this instance, being secured in the eyes 2 of the end ears 3 and the eyes 4 of the intermediate ears 5, see Fig. 5. This improved strain plate is adapted to serve for either a left-hand or a right-hand lead by merely turning the strain plate over, Fig. 1 showing the strain plate in position for a left-hand lead, Fig. 2 showing the strain plate in position for a right-hand lead. After this improved strain plate has been suspended in proper position by the guy wires, the main trolley wire 6 is engaged against the under side of the strain plate, said trolley wire adapted to engage the inclined guiding groove 7 which is formed on one end of the strain plate, an intermediate guiding groove 8, and an end 85 guiding groove 9 which is formed in said strain plate opposite to the groove 7.

Formed in said strain plate 1, intermediate of its ends, is a longitudinal slot 10, said slot having a pair of oppositely disposed recesses 11 formed adjacent each end. U-bolts 12 are then engaged against the under side of the trolley wire 6, adjacent the slot 10, and are engaged in the opposite recesses 11. A plate 13 is then mounted on each 95 U-bolt, said plates engaging on the top of the strain plate. When nuts 14 are tightened on the U-bolts, a portion of the main trolley wire 6 is drawn up into the slot 10, thereby firmly clenching and securing the main trolley wire to the strain plate.

The left or right lead of this improved strain plate is formed by having a portion 15 of said strain plate lead off at an angle from the main body portion. Formed on 105 the portion 15 is a circular portion 16 which has a circular groove 17 formed therein. The lead wire 18, when being secured to the

portion 15 of the strain plate 1, is engaged against the under side of the groove 17, then passed through the opening 19, then returned on top of said portion 15, and passed 5 around a clip 20 which is carried by a pair of clamping bolts 21.

Adapted to be engaged at each end of the strain plate 1, is a trolley wire approach 22. The ends 23 of each of said approaches are 10 adapted to be engaged in each recess 24 which is formed at the ends of the strain plate 1. Formed integral with each approach 22 is a horizontally arranged portion 25. Formed in each of said horizontal portions 15 are a pair of bolt holes 26, said bolt holes adapted to aline with the bolt holes 27 which are formed on the strain plate.

One end of the portion 15 of the strain plate has a recess 28 formed therein, said 20 recess being for the reception of one end 29 of another trolley approach 30, said approach 30 having a horizontal portion 31. Said portion 31 has a pair of bolt openings formed therein, said bolt openings adapted 25 to aline with the bolt openings 32 formed adjacent the recess 28 of the portion 15.

Adapted to be engaged against the under side of the strain plate 1 is a removable trolley frog 33, said trolley frog having trolley wheel engaging portions 34 and 35 30 which are adapted to engage against the under side of the main trolley wire 6, and a trolley engaging portion 36 which is adapted to be engaged adjacent the under side 35 of the lead trolley wire 18.

Formed at one end of each of the trolley wheel engaging portions 34 and 35 are a pair 40 of ears 37, each of said ears having bolt openings 38 which are adapted to aline with the bolt openings 27 of the strain plate 1 and bolt openings 26 of the approaches 22, there being bolts 39 passed through each set 45 of said alining openings. The ears 40, having bolt holes 41, are formed in one end of the trolley engaging portion 36. Said bolt holes 41 are adapted to aline with the bolt holes 32 of the strain plate 1, and the bolt holes of the trolley wire approach 30, said alining bolt holes relating to said approach 50 30 having bolts 42 passing therethrough.

With this arrangement of bolting the approaches and the trolley frog to the strain plate, the trolley frog is securely held in position.

55 An inverted groove 43 is formed on the under side of the aforesaid approaches for engagement with their respective trolley wires, there being depending flanges 44 formed on each side of said grooves which 60 are adapted to be clenched against the under side of the trolley wire.

When it is desired to remove the frog 33 on account of wear and to replace it by another frog of the same construction, the bolts 65 39 and 42 are removed from their respective

bolt openings and are replaced after the old frog has been taken down and a new one put in place. It is, therefore, seen that the guy wires and trolley wires are not disturbed on account of being permanently secured 70 to the strain plate. As afore mentioned, it is readily seen how the strain plate can be used for both right- and left-hand leads by merely reversing the same, it of course being necessary to have the trolley frogs made of 75 both left- and right-hand construction, Figs. 3 and 4 showing a right-hand lead frog.

It is obvious that an improvement of this character, which relates to trolley switch construction, when once assembled, can be repaired very quickly, thus cutting out considerable expense for labor.

What I claim is:

1. In a trolley switch, a strain plate for the support of a trolley frog having like 85 portions formed on the top and bottom side thereof so that said plate can be reversed relative to the adaptation of right or left hand frogs.

2. In a trolley switch, a strain plate, said plate being for the support of a right hand trolley frog, and means formed on said plate whereby said plate can be mounted in a reversed position relative to the supporting 90 of a left hand trolley frog.

3. A strain plate for trolley switch frogs adapted to be supported by guy wires, said plate having duplicate portions formed thereon whereby means are provided for reversibly mounting said plate relative to 100 the supporting of a right or left hand frog.

4. A strain plate for trolley switch frogs having like portions formed on the top and bottom thereof that are adapted to receive a trolley wire so that said plate can have 105 either its top or bottom portion engaged against a trolley wire.

5. In a trolley switch, a strain plate having a lead portion formed thereon, guy wires for sustaining said plate in a permanent 110 position, said plate adapted to support a trolley wire, said plate adapted to be mounted in a reversed position, and means formed on said lead portion whereby said lead portion can accommodate either a left or right 115 hand trolley lead.

6. In a trolley switch, a strain plate, said strain plate adapted to have a trolley wire secured thereto, a removably mounted trolley frog secured to said strain plate, and a 120 trolley wire approach adapted to be secured to said strain plate and said frog.

7. A strain plate for trolley switch frogs having like portions formed on the top and bottom thereof that are adapted to receive 125 a trolley wire so that said plate can have either its top or bottom portion engaged against a trolley wire to accommodate right or left hand trolley wire leads.

8. In a trolley switch, a strain plate, said 130

plate being adapted to be secured to a main line trolley wire, a lead trolley wire portion formed on said plate for the reception of a lead trolley wire, said plate having like portions formed on the top and bottom side thereof whereby either side of said plate can be placed uppermost so that said lead portion can be placed in either a right or

left hand position relative to the mounting of either a right or left hand trolley frog 10 thereto.

JOSEPH E. BURGESS.

In the presence of:—

S. W. CRAWFORD,
H. G. FLETCHER.
